UNITED STATES PATENT OFFICE.

EDWARD F. HANNON, SR., OF TULSA, OKLAHOMA.

ACCELERATOR-PEDAL FOOT-REST.

1,197,023.

Specification of Letters Patent.

Patented Sept. 5, 1916.

Application filed November 5, 1914. Serial No. 870,385.

To all whom it may concern:

Be it known that I, EDWARD F. HANNON, Sr., a citizen of the United States, residing at Tulsa, in the county of Tulsa and State 5 of Oklahoma, have invented certain new and useful Improvements in Accelerator-Pedal Foot-Rests, of which the following is a specification.

This invention relates to a device for supporting the foot of an operator adjacent the controlling pedal of an automobile, particularly the accelerator pedal.

One object of the invention is to provide a device of this character so constructed as 15 to be readily adjustable, whereby it may be made to conform to the individual characteristics, both of different types of machines and of different operators.

A further object is to provide a foot rest 20 constructed to be engaged by the instep of the operator's foot between the heel and toe, and pivoted so as to permit entire freedom of movement.

In order that the invention may be readily 25 understood, reference is had to the accompanying drawings, forming a part of this specification, and in which,

Figure 1 is a side view showing my improved foot rest as it appears in use, parts 30 being in section; Fig. 2 is a view of the foot rest itself, taken in a plane at right angles to Fig. 1; and, Fig. 3 is a perspective view of a shim block which I may employ.

Referring to the drawings in detail, 1 35 designates the accelerator pedal which may be of any desired construction, while 2 indicates the floor or footboard. My improved footrest comprises a supporting post 40 3, which is capable of sliding adjustment through a hole in the floor and through an apertured boss 4, preferably formed integral with a base plate 5. The post 3 is held in adjusted position by means of a set screw 6. 45 The base plate 5 is secured in position upon the footboard 2 by means of bolts 7, of which preferably four are employed.

At the upper end of the post 3 is a curved 50 U-shaped yoke 8, the yoke and post together forming a frame of Y-shaped configuration. Between the upper ends of this frame extends a foot supporting member 9, which is in the form of a U-shaped swinging stirrup having at its ends pintles 10 which turn 55 freely in openings in the Y-shaped frame.

It will be apparent from an inspection of

Fig. 1 that the instep of the operator's foot rests easily in this swinging stirrup 9, being held against lateral displacement and retained in such position that the toe can 60 readily engage the lever 1. The heel bears against one side of the stirrup and prevents the foot from slipping too far forward. It will be obvious that the stirrup may swing freely on its pintles so as to adapt itself to 65 any position which the foot may assume. By means of the set screw 6, the foot-rest may be adjusted in accordance with the requirements of any particular operator.

In order to insure the proper angle of the 70 post 3 relative to the operator, so that the thrust will be properly centered, I propose to provide a number of wedge-shaped shim blocks 11, such as shown in Fig. 3. These blocks will be thick on one side, as indicated at 12, and tapered to a feather edge on the other, as indicated at 13, the blocks being provided with a central hole 14, to accommodate the post 3, and with bolt holes 75 15 adjacent the corners. These blocks will, 80 of course, be of the same length and breadth as the base plate 5, so as to lie neatly thereunder.

It will be understood that a dealer will carry in stock a number of plates similar to 85 11, of varying thicknesses, so that when equipping an automobile with my improved foot-rest, a wedge-block of the proper thickness corresponding with the particular slope 90 of the footboard in question may be selected. In this way the angular relation between the post 3 and footboard may be determined as necessary to meet any given requirements.

What I claim is:

1. In a device of the class described, the combination with an automobile accelerator pedal of a foot rest disposed adjacent thereto, said rest having upright portions between which the foot is received and comprising a pivotally mounted foot supporting member constructed to engage with the instep of the foot between the toe and heel, thus constituting a heel stop to limit the forward movement of the foot, whereby the 105 fore part of the foot may freely bear upon said accelerator pedal, as desired.

2. In a device of the class described, the combination with an automobile accelerator pedal, of a foot rest mounted adjacent 110 thereto, said rest comprising a U-shaped frame into which the instep of the foot be-

5 tween the heel and toe is received, and supporting means for said frame, said supporting means projecting down through the floor of the automobile, and means for varying the extent to which the said supporting means so projects, whereby the height of said foot rest relative to the accelerator pedal may be adjusted as desired.

10 3. In a device of the class described, the combination with an automobile accelerator pedal, of a foot rest disposed adjacent thereto, said rest comprising a U-shaped frame, supporting means for said frame, and a swinging stirrup pivotally mounted between the legs thereof, and adapted to receive the foot of the operator between the heel and toe, whereby the toe may freely engage and actuate said accelerator pedal.

15 4. In a device of the class described, the combination with an automobile accelerator pedal, of a foot rest disposed adjacent thereto, said rest comprising a Y-shaped supporting frame, and a swinging stirrup mounted

between the legs thereof, and means for adjusting the height of said frame above the 25 automobile floor, whereby its relation to the said accelerator pedal may be varied as desired.

5. In a device of the class described, the combination with an automobile accelerator 30 pedal, of a foot rest disposed adjacent thereto, said rest comprising a Y-shaped supporting frame, and a swinging stirrup mounted between the legs thereof, means for adjusting the height of said frame, and means for 35 adjusting the angle between said frame and the automobile floor, whereby the relation of said frame to the operator and to the accelerator pedal may be varied as desired.

10 In testimony whereof I have affixed my 40 signature in presence of two witnesses.

EDWARD F. HANNON, SR.
